[57] CLAIM

The ornamental design for an illuminating badge, as shown and described.

DESCRIPTION

FIG. 1 is a perspective view as seen from the front, top and one side of an illuminating badge showing my new design;

FIG. 2 is a front elevational view thereof;

FIG. 3 is a side elevational view thereof, as seen from left to right;

FIG. 4 is a side elevational view thereof, as seen from the side opposite that shown in FIG. 3;

FIG. 5 is a top plan view thereof; and,

FIG. 6 is a bottom plan view thereof.

The rear view not shown, is plain and unornamented.
